UNITED STATES PATENT OFFICE.

BERNARD A. BELLING, OF BEAVER DAM, WISCONSIN, ASSIGNOR TO BELL MANUFACTURING CO., OF BEAVER DAM, WISCONSIN.

DRINKING CUP FOR STOCK.

1,405,478.

Specification of Letters Patent.

Patented Feb. 7, 1922.

Application filed June 4, 1921. Serial No. 475,116.

To all whom it may concern:

Be it known that I, BERNARD A. BELLING, a citizen of the United States, and resident of Beaver Dam, in the county of Dodge and State of Wisconsin, have invented certain new and useful Improvements in Drinking Cups for Stock; and I do hereby declare that the following is a full, clear, and exact description thereof.

10 My invention refers to drinking bowls for stock of that general type which is disclosed in my patent dated June 29th, 1920, No. 1344750. The general object of my invention is to provide a simple, economical and effective detachable bowl of the character mentioned, wherein the same may be conveniently removed or secured in place, and wherein the supply pipe to the bowl can be introduced conveniently from above or below, there being no projecting parts which would tend to injure the animal.

15 Specific objects of my invention are:

To provide a hollow water head having a receiving neck arranged to communicate with a water supply pipe which may extend from below or above.

20 To provide a clamp for supporting the head and through which the supply pipe can pass when it is positioned to feed from below.

25 To provide a depending finger in connection with the neck portion of the hollow head for engagement with the clamp.

30 To provide a throat between the finger and head adapted to receive the upper rear wall of a removable bowl and a pocket associated with the lower portion of the finger, in which a flange of the bowl is adapted to

35 socket.

35 To provide a vertically adjustable clip in straddled relation with the head neck for locking the bowl in position, the clip having a pair of wedge shaped locking feet which secure the bowl against movement both in a vertical and lateral direction.

40 To provide a valve controlled water head having a direct transverse connection to a feed pipe whereby channels or tortuous passageways are provided, to thus simplify the structure.

45 To provide a valve tappet which is of the knife-blade type for engagement with the bottom of a valve stem, whereby water discharged from the delivery port will flow in

an unbroken column, and thus avoid spattering.

With the above and other minor objects in view, the invention consists in certain peculiarities of construction and combination of parts, as are hereinafter set forth with reference to the accompanying drawings and subsequently claimed.

In the drawings:

Figure 1 represents a fragmentary sectional elevation of a drinking-bowl embodying the features of my invention, the section being indicated by line 1—1 of Figure 4.

Figure 2 is a side elevation of the same, with parts broken away and in section.

Figure 3 is a sectional plan view of the bowl mechanism, the section being indicated by line 3—3 of Figure 2.

Figure 4 is a detailed rear sectional view, the section being indicated by line 4—4 of Figure 1, and

Figure 5 is a detailed plan sectional view showing the bowl locking retaining means, the section being indicated by line 5—5 of Figure 4.

Referring by characters to the drawings, 1 represents a vertically disposed stanchion or standard to which is fitted a three-part clip for adjustably supporting the bowl parts upon the standard. The clip comprises a strap 2 and jaw members 3, which jaw members are secured to the standard and clip 2 by retaining bolts, as best shown in Figure 3. The jaw members have spacer lugs 3' intermediate of their ends, between which is clamped, in this instance, a vertically disposed water feed pipe 4, the same being held in position by a nut and bolt 5 which passes transversely through the jaw members. The jaw members terminate with inturned gripping teeth 6, which are nested in a recess 6' that is formed in a downwardly extending finger 7, which finger constitutes part of a hollow water head 8. The finger, as shown, is firmly gripped between the teeth 6 and one pair of the spacer lugs 3' of the jaw members 3.

The hollow water head is formed with a rearwardly extended channeled neck 9, which neck is positioned near the upper end of the water head, and extends transversely thereof for the reception of an elbow 4' that forms part of the water supply feed pipe 4. Obviously, owing to the

peculiar construction of the neck 9 with relation to the water head, the feed pipe can be adjusted so as to feed either from below, as shown in Figure 1 of the drawings, or it 5 can be given a half turn, whereby it will feed from above, in which case the pipe will not be grippingly held by the jaw members of the clip. This construction is material, due to the fact that in many installations, 10 it is often necessary to effect a coupling connection for the water supply from above. The depending finger 7, as shown in Figure 1, constitutes a part of the neck and is at its upper end spaced from the juxtaposed 15 wall of the cylindrical water head, whereby a throat 10 is formed at this point for a clearance space adapted to receive the upper edge of a rear wall 11 that constitutes part of a removable bowl 12.

20 The side walls 11' of the bowl are contracted with relation to the body of the bowl to form in conjunction with the rear wall 11 thereof, a rectangular cavity adapted to snugly engage the water head 8. The rear 25 wall 11 of the bowl is extended below the bottom thereof to form a locking rib 11'', which rib, as shown, is nested within a bowl receiving pocket 13 that is formed in a forward extended nose 7' of the finger 7. As 30 best shown in Figures 1 and 4 of the drawings, the head neck 9 is formed with an annular groove 9', which groove is adapted to receive a vertically adjustable stirrup 14. The legs of the stirrup terminate with wedge 35 shaped locking feet 14' that are formed with forward extended toes 15 having locking shoulders 15', which locking shoulders are arranged to engage the upper and inner edges of the rear bowl flange 11. Upper 40 vertical movement of the stirrup is limited by a tooth 15'', which projects from the rear portion of each locking foot and which tooth engages an offset notched tooth 16 of the neck 9 at a point, where said neck merges 45 into the finger 7, the same being particularly shown in Figures 2 and 4.

As best indicated in Figure 4, the outer faces of the locking feet 14' are slightly tapered to form wedges, which wedges engage 50 the upper inner edge surface of the contracted bowl walls 11'-11'', whereby the bowl when adjusted in position is firmly held against lateral play.

As best shown in Figure 5, the toe extensions 15 at their outer ends engage the circular wall of the water head, whereby they are held against forward swing under sagging load strain of the bowl, bearing in mind that the bowl will tend to rock forward, 55 with the pocket 13 as a point of oscillation. The rear wall of the bowl 12, in conjunction with the bottom flange 11', is of such dimensions that when said flange rests in the pocket 13, the bowl can be rocked 60 backward slightly, so that the upper edge

thereof will engage a shoulder 10' formed in the adjacent inner wall of the finger 7. Hence, when the bowl is in its proper position for locking, it is confined against vertical movement between the shoulder 10 and 70 the pocket 13. The bowl is held against sagging or rocking motion upon the finger support by the stirrup foot 15. Obviously, all that is necessary when it is desired to remove the bowl is to lift the stirrup 75 slightly, whereby the upper edge of the bowl is rendered free to swing, and thereafter the edge of the bowl wall 11 is shifted into the throat 10, whereby clearance is effected between the pocket rest, in connection with the nose 7', and thereafter the bowl can be withdrawn readily. 80

The water head is provided with an open end closed by a plug 16, and the bottom of the head is provided with a port 17 which is 85 controlled by spring actuated valve having a stem projecting therethrough, which is of the cross-type, or finned. The stem is actuated by a skeleton lever 18, which lever is 90 suitably pivoted to the head 8 and is provided with a backwardly extended knife-like finger 18', which finger engages the valve stem. Owing to the narrowness in width of the finger, when the lever 18 has 95 been actuated by the animal to open the valve, a steady stream will be caused to flow, which stream will not be obstructed by the finger 18'.

While I have shown and described specifically one exemplification of my invention 100 in all of its details, obviously I may vary the structural features of the same without departing from the scope of the claims.

I claim:

1. A stock drinking bowl comprising a 105 hollow head, having a transversely disposed channelled neck extending therefrom, a finger depending from the neck terminating with a bowl receiving pocket, the base of the finger being spaced from the head 110 to form a receiving throat, a removable bowl having an end wall provided with a bottom flange, and contracted rear side walls adapted to encase the head, the upper edge of the rear wall being arranged to 115 enter the receiving throat whereby the bowl is inserted, and thereafter shifted downwardly to cause its bottom flange to locking engage the receiving pocket, and a vertically adjustable stirrup mounted upon 120 the neck having locking feet for engagement with the upper edge of the bowl, whereby the latter is held against both horizontal and vertical movement.

2. A stock drinking bowl adapted to be 125 adjustably secured to a standard comprising a hollow head, having a transversely disposed channelled neck extending therefrom, a fluid delivery pipe adjustably fitted to the neck, a finger depending from the neck 130

- being provided with an upper receiving throat and a lower pocket, a shoulder on said finger, a removable bowl having contracted side walls, and a rear transverse wall 5 terminating with a bottom flange, the same being adapted to rest within the finger pocket, and the upper edge thereof being in engagement with the finger shoulder, and a reciprocative stirrup mounted upon the 10 neck, the stirrup having locking feet for engagement with the upper faces of the contracted portion of the bowl, whereby said bowl is locked against movement in all directions.
- 15 3. A stock drinking bowl adapted to be adjustably secured to a standard comprising a hollow head, having a transversely disposed channeled neck extending therefrom, a fluid delivery pipe fitted to the neck, 20 a finger depending from the neck being provided with an upper receiving throat and a lower pocket, a shoulder on said finger, a removable bowl having contracted side walls, a rear transverse wall terminat- 25 ing with the bottom flange, the same being adapted to rest within the finger pocket,
- and the upper edge thereof being in engagement with the finger shoulder, a reciprocative stirrup mounted upon the neck, the stirrup having locking feet for engagement 30 with the upper faces of the contracted portion of the bowl, whereby said bowl is locked against movement in all directions, and a three-part clip for engagement with the standard feed pipe and head finger, 35 whereby the parts are adjustably anchored.
4. A stock water bowl comprising a channeled head having a depending bowl supporting finger, a bowl adapted to encase the head having contracted parallel side 40 walls and an end wall adapted to encompass the head and to rest upon the finger, and a reciprocative stirrup having feet for locking the bowl, the feet being adapted to have wedging engagement between the head 45 and bowl walls.

In testimony that I claim the foregoing I have hereunto set my hand at Beaver Dam, in the county of Dodge and State of Wisconsin.

BERNARD A. BELLING.
